EDWARD D. GLEASON, OF PHILADELPHIA, PENNSYLVANIA, ASSIGNOR TO
ELLSWORTH A. HAWTHORNE AND HORACE SHEBLE, OF PHILADELPHIA,
PENNSYLVANIA.

SOUND-BOX FOR TALKING-MACHINES.

SPECIFICATION forming part of Letters Patent No. 730,110, dated June 2, 1903.

Application filed July 30, 1902. Serial No. 117,703. (No model.)

To all whom it may concern:

Be it known that I, EDWARD D. GLEASON, a citizen of the United States, residing in Philadelphia, Pennsylvania, have invented 5 certain improvements in Sound-Boxes for Talking-Machines, of which the following is a specification.

The objects of my invention are to provide a simple and inexpensive form of elastic 10 mounting for the stylus-arm of a sound-box, to amplify the sound by the employment of a plurality of diaphragms instead of the single diaphragm ordinarily used, and to provide a more compact sound-box structure than 15 those heretofore made. These objects I attain in the manner hereinafter set forth, reference being had to the accompanying drawings, in which—

Figure 1 is a sectional view of a single-diaphragm sound-box constructed in accordance 20 with my invention. Fig. 2 is a similar view illustrating a different location of stylus-lever constituting one of the features of the invention. Figs. 3 and 4 are sections of double-diaphragm sound-boxes constructed in accordance 25 with the invention, and Figs. 5, 6, 7, and 8 are front views of the sound-boxes shown in Figs. 1, 2, 3, and 4, respectively.

The sound-box consists of a tubular stem 30 1, with enlarged or cup-shaped end 2, containing the diaphragm 3, which may be mounted in the casing of the sound-box in any suitable manner, the diaphragm in the present instance being seated upon an internal annular shoulder formed in the enlarged portion 2 of the sound-box and being retained in position thereon by means of an elastic ring 4, inserted into an annular groove in the inner face of said portion 2 of the box.

Suitably secured to the outer face of the sound-box shown in Fig. 1 is a short tube 5, the top of which is closed by a thin diaphragm 6, which may be an integral part of the tube 5 or may be a separate piece brazed or otherwise suitably secured to said tube. Projecting outwardly from the center of this diaphragm 6 is a post 7, which carries the stylus-lever 8 of the instrument, the latter being curved downwardly at the inner end, so as

to bear upon the central portion of the diaphragm 3, to which, if desired, it may be suitably secured, the outer end of the stylus-lever having detachably secured therein the stylus 9, which engages with the walls of the waved or undulating groove of the record and is vibrated thereby, this vibration being transmitted through the stylus-lever to the diaphragm 3 in order to cause the vibrations of the latter, whereby the sound-waves are reproduced.

The thin diaphragm 6 provides a mounting for the stylus-lever, which is sufficiently elastic or resilient to permit ready vibration of the same, but which eliminates all loose joints or points of contact between the stylus-lever and sound-box casing, said stylus-lever and its mount in my improved sound-box being substantially one part, so that any chatter or vibration due to loosely-fitting joints or points of bearing between the stylus-lever and casing is effectually prevented.

In that form of sound-box shown in Fig. 2 the tube 5 and its diaphragm 6 are disposed upon the sound-box casing in a manner different from that represented in Fig. 1, and the stylus in this case passes through a central opening in the diaphragm, to which the stylus-lever may be secured by brazing, soldering, or by other means, one of such other means being the reduction in the size of the stylus-lever, so as to form a shoulder bearing against the outer face of the diaphragm, the reduced portion of the lever being threaded for the reception of a nut 10, which bears upon the inner face of the diaphragm and serves to securely confine the stylus-lever thereto. In this form of my improved sound-box, moreover, the stylus-lever is located on the inner side of the diaphragm instead of upon the outer side of the same, as usual, the sound-box casing having in one side an opening 11 for the passage of the stylus-lever. By this means the sound-box structure is rendered compact, and the stylus-lever is protected by the sound-box casing, so that it is not liable to injury.

In order to amplify the sound, I prefer in some cases to use a sound-box having a dou-

ble diaphragm, and in Figs. 3 and 4 I have shown two different forms of such a sound-box, that shown in Fig. 3 having outside stylus-levers and that shown in Fig. 4 having 5 an inside stylus-lever.

In the structure shown in Fig. 3 the mounting of the stylus-lever 8 is substantially similar to that shown in Fig. 1; but the diaphragm 6 is perforated and the post 7 is continued 10 through the same and through the tube 5 in the form of a supplementary stylus-lever 8^a, which bears upon the diaphragm 3^a, the latter being opposed to the diaphragm 3, upon which the stylus-lever 8 bears, and the tubular stem 1 of the sound-box projects laterally 15 from the casing 2, so as to communicate with the chamber between the two diaphragms.

In the double-diaphragm box (shown in Fig. 4) the stylus-lever is mounted in the same 20 manner as in Fig. 2, but it has a T-shaped inner end, one arm of the T bearing against the diaphragm 3 and the other against the diaphragm 3^a. In this sound-box, also, an elbow-tube 1^a replaces the straight tubes of the 25 sound-boxes previously described, the object being to provide a horn-attaching portion projecting at right angles to the diaphragm, while at the same time retaining the lateral communication with the sound-chamber necessitated by the use of the two diaphragms. 30

Having thus described my invention, I claim and desire to secure by Letters Patent—

1. A sound-box for talking-machines in 35 which are combined a casing, a diaphragm mounted therein, a tube projecting from said casing, and also carrying a diaphragm, and a stylus-lever mounted upon the latter diaphragm, substantially as specified.

2. A talking-machine sound-box having a 40

casing containing a diaphragm, a stylus-lever bearing upon the inner face of said diaphragm, and projecting laterally through the casing, and a tube surrounding said stylus-lever and carrying a diaphragm upon which 45 the same is mounted, substantially as specified.

3. A talking-machine sound-box having a plurality of diaphragms, a duplex stylus-lever having a stylus-lever and a bearing upon 50 each of said diaphragms, a tube projecting from said sound-box, and a diaphragm closing the end of said tube and providing an elastic support for the stylus-lever, substantially as specified.

4. A talking-machine sound-box having a plurality of diaphragms, a duplex stylus-lever having a single stylus and a bearing upon the inner face of each of said diaphragms, a tube projecting from the sound-box and surrounding the stylus-lever, and a diaphragm closing the end of said tube and providing an elastic mounting for said stylus-lever, substantially as specified.

5. A talking-machine sound-box having a 65 plurality of diaphragms each exposed upon its outer face, a tubular stem projecting laterally from the sound-box and communicating with the chamber between the two diaphragms, and a duplex stylus-lever having a 70 single stylus and a positive connection with each of said diaphragms, substantially as specified.

In testimony whereof I have signed my name to this specification in the presence of 75 two subscribing witnesses.

EDWARD D. GLEASON.
